UNITED STATES PATENT OFFICE.

ESTER M. SEALY, OF FORT SHAFTER, TERRITORY OF HAWAII.

UNDERSCORER FOR TYPEWRITERS.

1,349,107.

Specification of Letters Patent. Patented Aug. 10, 1920.

Application filed December 12, 1918. Serial No. 266,444.

To all whom it may concern:

Be it known that I, ESTER M. SEALY, a citizen of the United States, residing at Fort Shafter, in the Territory of Hawaii, 5 have invented certain new and useful Improvements in Underscorers for Typewriters, of which the following is a specification.

This invention relates to underscorers for 10 typewriters, and more particularly to a device by means of which predetermined words may be underscored simultaneously with the typing operation.

One of the main objects of the invention is 15 to provide a device of the character stated of simple construction and operation by means of which words which are written in first case or second case letters may be easily underscored simultaneously with the typing thereof. A further object is to provide an 20 underscorer which may be readily applied to a typewriting machine of standard construction. Another object is to provide an underscorer and means in connection therewith for moving the underscorer either into 25 or out of operative position, means also being provided for moving the underscoring element into position to underscore either first case or second case letters simultaneously 30 with the shifting of the carriage or key board for this purpose. Further objects will appear from the detailed description.

In the drawings:

Figure 1 is a front view of an underscorer 35 constructed in accordance with my invention as applied, the key board and associated parts of the typewriter being omitted for the sake of clearness,

Fig. 2 is a perspective front view of the 40 underscorer and the control and operating means therefor,

Fig. 3 is a side view of the underscorer operating and releasing keys and the associated parts in depressed position,

Fig. 4 is a similar view showing the keys 45 in raised position.

Fig. 5 is a section taken substantially on line 9—9 of Fig. 8,

Fig. 6 is a side view of the underscorer 50 and associated parts showing the relative positions of the underscorer and the type bar, and the platen roll, when the underscorer is in depressed or inoperative position.

Fig. 7 is a similar view showing the underscorer raised for underscoring second case 55 letters,

Fig. 8 is a similar view to Fig. 7 with the underscorer in position for underscoring first case letters,

Fig. 9 is a section taken substantially on 60 line 13—13 of Fig. 6,

Fig. 10 is a perspective detail of the outer securing block of the underscorer.

The typewriter A may be of any suitable construction and is provided with the usual 65 carriage B slideable thereon and having the platen roll D paper guide C and associated parts. In front of the roll is mounted a graduated plate E adjacent which is provided the usual fork ribbon guide F. This 70 guide is provided with the usual central slot G across which is passed the ribbon H taken from the spools I in the usual manner. The typewriting machine illustrated and the parts thereof referred to, are all of standard construction, the particular machine shown being what is known on the market 75 as the Royal typewriter.

A rod 1 is mounted beneath the key board and the associated parts of the typewriter 80 and extends the full length of the machine. This rod is reduced at each end to provide a gudgeon 2. These gudgeons fit into co-operating recesses or bores 3 formed in supporting screws 4 which are threaded through 85 the end plates 5 of the frame of the typewriter. By this means, rod 1 is detachably secured in the typewriter and is mounted therein for rocking movement about an axis extending longitudinally of the machine. 90

A sleeve 6 is secured on rod 1 adjacent one end thereof by means of a set screw 7 threaded through the sleeve and engaging the rod. A coil tension spring 8 is mounted about the end portion of the rod adjacent 95 the outer end of sleeve 6 and has one end bent substantially at right angles to provide a finger 9 which engages into a co-operating recess in the adjacent end of the sleeve. The outer end portion of spring 8 is straightened 100 to provide an arm 10 having at its outer end a finger 11 disposed substantially at right angles thereto, this finger engaging into the adjacent end plate 5 of the typewriter frame. Spring 8 acts to rock sleeve 6 forwardly and upwardly and, through the sleeve, also serves to cause similar movement of rod 1. Sleeve 6 is provided with an integral forwardly projecting lever 12. This lever is provided at its outer or forward 105 end with an integral upwardly directed finger 13 at the upper end of which is secured

110

an operating head or key 14. A releasing lever 15 is pivotally secured at its inner end to lever 12, intermediate the ends thereof, by means of a screw or pin 16. Releasing lever 15 is normally held in raised position by a wire spring 17 which engages about the lever in advance of the pivotal axis thereof, the inner end of this spring being engaged about the lower edge portion of lever 12. A substantially rectangular finger or stud 18 is carried by the lever 15 adjacent the inner end thereof and, being positioned in front of the spring, serves to prevent displacement of this member when the releasing lever is rocked. Lever 15 is provided, at its outer end, with a standard 19 at the upper end of which is secured a head or key 20. The upward movement of lever 15 under the influence of spring 17 is positively limited by a stud 21 carried by lever 12 and engaging the upper edge of lever 15. As will be noted, lever 15 projects forwardly beyond lever 12 and engaging the upper edge of lever 15. As will be noted, lever 15 projects forwardly beyond lever 12 so as to permit and facilitate independent operation thereof. Lever 12 is provided, at its lower forward corner, with a substantially V-shaped head 22 having the forwardly projected point 23 the upper face of which is disposed in parallelism with lever 12 and is adapted to be engaged by the head 24 of a pawl 25 which is rockably mounted on a stub shaft 26 which projects from the adjacent end plate 5 of the typewriter frame. This pawl is normally forced inwardly toward lever 12 by a wire spring 27 coiled about the bearing sleeve 28 which supports stub shaft 26, the inner portion of this spring bearing against the forward or outer face of pawl 25, and the outer end of this spring being secured in end plate 5. When operating lever 12 is rocked downwardly, the forward downwardly and inwardly inclined face of point 23 will engage the inner end of the head 24 of the pawl so as to rock the pawl outwardly. As soon as the upper edge of head 24 is moved into coincidence with the upper surface of the head of the pawl, the pawl will be moved inwardly so as to bring the head thereof above point 23, thus locking lever 12 in depressed position, as in Fig. 7. When it is desired to release the lever, this is accomplished by depressing the releasing lever 15 so as to bring the lower edge of the intermediate downwardly and inwardly inclined portion 15^a into engagement with the inner end of head 24 of the pawl. This results in rocking the pawl outwardly such a distance as to release lever 12 which is then returned to its initial position by tension spring 8. When the lever 12 is raised, head 24 of the pawl will engage a depending lug 29 provided at the lower end of the V-shaped head 22 of the

lever 12 for this purpose. This lug is so related to lever 12 as to maintain the pawl in the position illustrated in Fig. 9 when the operating lever is in raised position so that, when the operating lever is depressed, the pawl will be rocked inwardly so as to engage over the point 23 of head 22 in the manner previously described. By means of the operating lever 12 and releasing lever 15, the shaft 1 may be rocked a predetermined distance in either direction, and secured in rocked adjustment, as will be obvious.

A collar 30 is loosely mounted on the rod 1 at the longitudinal center thereof. This collar is normally rocked forwardly and downwardly by means of a coil tension spring 31 which is mounted about rod 1 adjacent one end of the collar, one end of this spring being secured in one end of collar 30 as at 32, the other end of the spring being secured to the rod by means of a screw 33, or in any other suitable manner. A collar 34 is secured on rod 1 by means of a set screw 35 and is positioned closely adjacent the other end of collar 30. Collar 34 is provided, at its inner end, with an integral axially extending lug 36 which projects into an arcuate groove or recess 37 formed in the adjacent end of collar 30. This lug serves to positively limit rotary movement of collar 30 in either direction relative to collar 34. By means of set screw 35, collar 34 may be secured in rotary adjustment on the rod so as to vary the portion of rod 1 about which sleeve 31 is rocked. An arm 38 is formed integral with sleeve 30 and projects rearwardly therefrom. The rearward end of this arm is bifurcated to form a fork 39. When the rod 1 is rocked downwardly and forwardly, lug 36 will be moved out of engagement with sleeve 30 at the rearward end of slot 37 thus permitting the sleeve to be rocked downwardly and forwardly under the influence of spring 31. By this means, when operating lever 12 is depressed and locked in this position, the arm 38 will be rocked upwardly and resiliently held in raised position by spring 31, for a purpose to be disclosed.

The arms of fork 39 at the inner end of arm 38 are provided with longitudinally extending extended alined slots 40. These slots receive a pin 41 which is inserted through an eye 42 provided at the lower end of the connecting rod 41 which is inserted through an eye 42 provided at the lower end of the connecting rod 43, thus securing the rod to the arm by pin and slot connections. A substantially rectangular or cubical securing block 47 is secured on the upper end of rod 43. This block is provided, on its inner face, with a central rib 48 and has a central bore 49 adapted to receive the shank of a securing screw 50. Screw 50 is adapted

to fit snugly through a longitudinal slot 51 provided through the body 52^a of the underliner 52 adjacent the lower end thereof. The block 47 coöperates with a securing plate 53 positioned adjacent the inner face of the body of the underliner. This plate is provided with a central recess or slot extending the full width thereof which is adapted to snugly receive the lower end portion of the shank of the underliner and the rib 48 of block 47. Securing screw 50 is inserted through block 47 and threaded through the plate 53, the block and plate coöperating to rigidly secure the underliner to the upper end of rod 43, the rib and the slot in plate 53 effectually preventing all looseness or play of the underliner. As will be noted more clearly from Figs. 1 and 2, the slot 51 is of greater length than the rib 48 thus permitting independent vertical adjustment of the underliner rendering it possible to secure very accurate set or adjustment of this member. Securing plate 53 is provided, at its lower end, with a finger 54 formed integral therewith. This finger projects beneath the upper horizontal arm 46^a of stop bar 46 and serves to positively limit upward movement of rod 43 and consequently, the underliner carried thereby. Arm 54 projects through the alined slots 55 and 56 in the ribbon guide. As will be noted more clearly from Fig. 13 of the drawings, the body portion 47^a of block 47 is reduced to form lateral flanges 47^b at the outer end of the block, and plate 53 corresponds in width to the outer end of the block. The plate and block thus coöperates to produce a guide head having lateral vertical grooves which receive the edge portions of the guide plate 61 secured on supporting plate 57 in front of the ribbon guide F, plate 61 being provided with a central slot 61^a which receives the guide bar, the head and plate coöperating to guide and brace the underscorer during its vertical movement.

Underliner 52 is provided, at the upper end of shank 52^a thereof, with a rectangular or substantially square head 58 which projects forwardly and rearwardly of the shank. The inner end of the inner arm of this head is beveled or rounded to provide a striking or marking element 59, and the outer end of the outer arm 60 is straight and disposed in parallelism with the shank. Head 58 is of such length that, when the underliner is in operative position, the inner end of arm 59 of the head will be positioned closely adjacent the roll D. When the type bar 62 of the typewriter is raised by means of the key in the usual manner, the head 58 of the underscorer will be positioned between type head 63 of the type bar and the platen roll so as to have the outer end of arm 60 engaged by the bar 64 of the type head, thus forcing the marking element at the inner end of arm 59 inwardly toward the platen so as to produce a short line on the paper being typed upon. As stated a stop bar 46 acts to positively limit upward movement of the underscorer. This stop bar is carried by the carriage of the typewriter which, in the particular type of machine illustrated, is operated by the usual shift key so as to be raised or lowered according to whether it is desired to use first case or second case letters. When the operating lever 12 is in normal or raised position, the arm 38 is rocked downwardly and rearwardly so as to maintain the underscorer in inoperative or lowered position, where it will not be struck by the type head 63 of a type bar 62, as illustrated in Fig. 6. When lever 12 is secured in depressed position, the underscorer will be raised into such position as to bring the head 58 thereof in position closely adjacent the platen roll 61 and at such a height as to be closely adjacent the second case letter block 65 carried by the type head 63, when the type bar 62 is raised. When the underscorer head 58 is in this position, when the type bar 62 is operated so as to cause the letter block 65 to strike the paper placed about the platen roll D, the bar 64 of the head will act to strike head 58 so as to simultaneously cause the production of a line beneath the particular letter which has been struck. In this manner, any desired letters or words may be underscored simultaneously with the typing thereof. This operation is illustrated in Fig. 7. When the carriage is raised so as to cause the first case letters carried by the first case letter block 66 to strike the platen, the underscorer will also be raised by means of spring 31 due to the fact that the stop bar 46 is raised with the carriage. The underscorer head 58 will now occupy a position intermediate the letter blocks 65 and 66 when the type bar is operated, as illustrated in Fig. 8. To permit proper operation of the underscorer when in this position, I provide an opening 67 through shank 52^a adjacent the head 58, this opening being so positioned as to permit the letter block 65 to pass therethrough when type head 63 is raised, as illustrated. By this means a line is produced beneath the capital or first case letter which is typed simultaneously with the typing of said letter. In Figs. 6 to 8 inclusive, illustrating the three stages of operation of the underscorer, the ribbon guide, ribbon, and associated parts, and the papers being typed upon has been omitted to avoid confusion and more clearly illustrate the operation of the mechanism.

In the particular form of mechanism illustrated, I have shown the stop bar for limiting the upward movement of the underscorer as mounted on the carriage, this carriage being adjusted vertically to change 130

from one case to the other. In machines where the key board is shifted instead of the carriage, the stop members would of course, be connected to the key board so as 5 to move therewith. In either case, the operation of the mechanism will be the same. The position of the stop or limiting bar corresponds to the adjustment which is made to change from one case to the other. Of course in applying the device to typewriters of various makes, it may be necessary to 10 make changes in the details of construction and arrangement of the various parts thereof and in the mechanism, and I intend to include in this application all such variations, as fall within the appended claims, and do not desire to be limited to the specific 15 construction illustrated except in so far as limitations may be imposed by the claims.

20 What I claim is:

- 21 1. In underscoring means, an underscorer provided with a head at its upper end 25 adapted to be engaged by the type head of a type bar of a typewriter upon which the underscorer is mounted when the head thereof is brought into position adjacent the platen roll of a typewriter and the type bar is operated, a stop member carried by the typewriter, a stop member secured to the underscorer and coöperating with the stop member carried by the typewriter so as to 30 positively limit upward movement of the underscorer so as to cause movement thereof in accordance with the vertical movement of the stop member carried by the typewriter, the stop member carried by the typewriter being adjustable in accordance with adjustment of the shifting mechanism of the typewriter when shifting from one case to another.
- 22 40 2. In underscoring means, an underscorer provided at its upper end with a head 45 adapted to be engaged by the type head of a type bar when the underscorer is positioned closely adjacent the platen roll of a typewriter upon which it is mounted, a stop member carried by said underscorer, a stop member carried by the typewriter and co-operating with the stop member of the underscorer to limit upward movement of the underscorer, said stop member carried by the typewriter being connected to the shifting mechanism of the typewriter so as to be adjusted vertically in accordance with 50 the adjustment of the shifting mechanism, means for exerting upward pressure on the underscorer, and means independent of the stop member for locking the underscorer against upward movement.
- 23 55 3. In underscoring means, the combination 60 with a typewriter of a rod rockably supported by the frame thereof, means for rocking said rod in either direction and for securing it in rocked adjustment, an underscorer connected to said rod so as to be actu-

ated thereby, and provided at its upper end with a head adapted to be struck by the type head of the type bar of the typewriter when moved in position closely adjacent the platen roll of the typewriter, and means for 70 varying the vertical adjustment of the underscorer in accordance with adjustment of the shifting mechanism of the typewriter when being shifted from one case to another so as to bring the head of the underscorer 75 into such position as to underscore the letters typed at any given time.

4. In underscoring means, the combination with a typewriter of a rod rockably supported thereby, an underscorer connected 80 to said rod so as to be adjusted vertically thereby when the rod is rocked, said underscorer being provided at its upper end with a head adapted to be struck by the type head of a type bar when positioned adjacent the 85 platen roll of the typewriter, and means for exerting upward pressure on the underscorer so as to raise the same, means for limiting the upward movement of the underscorer and for adjusting the underscorer 90 vertically in accordance with adjustment of the shifting mechanism of the typewriter when shifting from one case to another so as to bring the head of the underscorer into position to underscore either first case or 95 second case letters, and means for normally holding the underscorer in lowered position so as not to be struck by the type head.

5. In underscoring means, the combination with a typewriter of a rod rockably 100 mounted therein, an underscorer connected to said rod so as to be adjusted vertically thereby when the rod is rocked, said underscorer being vertically adjustable independently of the rod and having an underscoring head at its upper end adapted to be engaged by the type head of a type bar when positioned adjacent the platen roll of the typewriter, means for exerting upward pressure on the underscorer so as to raise it 110 into operative position, and means for locking the underscorer in lowered or inoperative position.

6. In underscoring means, the combination with a typewriter, of a rod rockably 115 mounted therein, an arm projecting radially from the rod and loosely mounted thereon, an underscorer connected to said arm so as to be moved vertically when the arm is rocked, resilient connections between the 120 arm and the rod for normally rocking the arm upward so as to raise the underscorer, means for limiting the upward movement of the underscorer so as to bring the same into position when in operation to 125 be struck by the type head of a type bar so as to produce a mark upon a sheet of material placed upon the platen roll of the typewriter, means for rocking said rod and for maintaining it in rocked adjustment, 130

- and connections between the rod and the arm for permitting limited independent movement of the arm about the bar so as to raise the underscorer when said bar is 5 rocked upon its extreme position in one direction, said connections being adapted to rock the arm downwardly so as to lower the underscorer and positively prevent upward movement thereof when the bar is rocked 10 into its extreme position in the other direction.
7. In underscoring means, the combination with a typewriter, of a rod rockably mounted therein, an arm projecting radially from the rod and loosely mounted thereon, an underscorer connected to said arm so as to be moved vertically when the arm is rocked, resilient connections between the arm and the rod for normally rocking 15 the arm upwardly so as to raise the underscorer, means for limiting the upward movement of the underscorer so as to bring the same into position when in operation to be struck by the type head of a type bar so 20 as to produce a mark upon a sheet of material placed upon the platen roll of the typewriter, means for rocking said rod and for maintaining it in rocked adjustment, and connections between the rod and the 25 arm for permitting limited independent movement of the arm about the bar so as to raise the underscorer when said bar is rocked into its extreme position in one direction, said connections being adapted to 30 rock the arm downwardly so as to lower the underscorer and positively prevent upward movement thereof when the bar is 35
- rocked into extreme position in the other direction, the connections between the arm and the bar being adjustable so as to vary 40 the extreme vertical distance through which the underscorer may be lifted when the bar is rocked into such position as to release the arm.
8. In underscoring means, the combination with a typewriter of a bar rockably mounted therein, means for securing the bar in rocked adjustment in either direction, and an underscorer connected to said bar so as to be adjusted vertically thereby 45 when the bar is rocked, said underscorer being provided at its upper end with an underscoring head adapted to be engaged by the type head of a type bar when positioned adjacent the platen roll of the typewriter, the underscorer being further provided adjacent said head with an opening through its shank to receive the letter block for the lower case letter of the type head 50 when the underscorer head is in position to 55 underscore first case letters, and means for limiting upward movement of the underscorer and for adjusting the underscorer so as to underscore either first case or second case letters in accordance with adjustment 60 in the shifting mechanism of the typewriter.

In testimony whereof I affix my signature in presence of two witnesses.

ESTER M. SEALY.
